SUPPORTING MEANS FOR HOSIERY, ETC

Filed Aug. 2, 1930

UNITED STATES PATENT OFFICE

ANDERSON C. GRASHAM, OF BURLINGTON, NORTH CAROLINA, ASSIGNOR OF ONE-HALF
TO GEORGE D. SMITH, OF BURLINGTON, NORTH CAROLINA

SUPPORTING MEANS FOR HOSIERY, ETC.

Application filed August 2, 1930. Serial No. 472,670.

My invention is an improvement in hosiery and relates more especially to the provision of means for supporting a sock or stocking so that it will retain its position on the leg of the wearer.

It is customary to support socks and stockings by different forms of hose-supporters or garters, in some instances employing elastic bands encircling the garment as well as embedded in the material by the use of hems or pockets and in other ways, but devices of this kind are usually of such nature as to impair the neat appearance of the garment and increase the cost of production.

The principal object of my invention therefore is to provide an elastic supporting means for hosiery, anklets, and other knitted garments, including sweaters, etc., in which several lengths of elastic cord are knitted within the garment during manufacture of the same, whereby the elastic cords which serve to hold the garment in place will not affect its neat appearance.

A further object of my invention is to incorporate the lengths or strands of elastic cord in the knitted garment so that the threads or yarn forming the ribs of the fabric will intimately engage said elastic cords to prevent creeping of the latter and increase their effectiveness in causing this part of the garment to closely fit the leg or other part of the body for which the garment is made.

With these principal objects in view my invention consists in providing the upper or open end portion of a garment, as well as other portions thereof requiring a close fit, such as hosiery, sweaters, etc., with separate strands of elastic cord knitted into the fabric with the contiguous ends preferably turned back into the material; all as hereinafter fully described and more specifically set forth in the appended claims.

In the drawings:

Figure 1 is an elevation of a sock illustrating the application of the elastic cords for supporting the article in position on the wearer, and to provide for an expansion of the toe portion of the sock.

Fig. 2 is an enlarged view of the upper

end of the sock showing the method of incorporating the elastic cords in the threads of the material of which the sock is made,

Fig. 3 is a transverse sectional view on the line 3—3 of Fig. 2,

Fig. 4 is an elevation of the upper portion of a stocking or sock showing a modification in the manner of knitting the ends of the elastic cords into the fabric, and

Fig. 5 is a similar view illustrating a further modification in which a longer strand of elastic cord is used and floated around the sock several times during the knitting operation.

In the drawings I have illustrated my invention of elastic means for supporting a garment in place as applied to a sock, but it will be understood that the idea may be carried out in connection with other articles of wearing apparel where it is desired that certain parts thereof closely fit the wearer. In its application to a sock, 9, the upper end portion 10 thereof is provided with two or more rows 11, 11 of elastic cord, preferably in the form of strands spaced apart and located near the open end of the sock, said strands being of such length as to extend entirely around the sock. The ends 12 of the elastic cord may terminate close to each other as shown in Fig. 2 of the drawings, or may overlap, but are preferably turned back into the fabric and knitted therewith as shown at 13 in Fig. 3.

I prefer to use elastic strands or cords of very small diameter, approximating the size of the thread or yarn used in knitting the sock so that it will not materially alter the neat appearance of the article, and these elastic strands or cords are incorporated in the fabric of which the sock is made during the knitting of the same. The elastic cords or strands may be of nude or covered rubber, and in the latter instance the thread cover may be of a color to suit that of the thread or yarn used in making the top of the hosiery. When the article is made on a knitting machine the strands or lengths of elastic cord are picked up and knit into the fabric with the thread or yarn thereof, as will be understood by those familiar with knitting ma-

chines, and it will be noted that the threads 14 forming the ribs of the upper part of the hosiery will pass around the elastic cords to intimately engage the same and with the 5 other strands of yarn hold them securely in place to prevent creeping of the ends.

By reference to Fig. 1 it will be seen that I also propose to provide for the stretching of the toe portion 15 of hosiery by incorporating elastic cords 16 in the material during 10 the formation of this portion of the sock so that said toe portion will stretch or yield to not only provide a better fit but also increase the wearing qualities of the sock by reducing 15 wear at this point.

In the modification shown in Fig. 5 I propose to provide the several spaced apart 20 rows of elastic cord by using a single length 18, and in this instance the said elastic cord is floated around this portion of the hosiery during the knitting operation, the ends 19 being turned abruptly so as to tie or anchor 25 them into the fabric.

By providing the top of a sock or stocking 25 with several rows of elastic cords spaced apart from each other and embodied in the fabric as hereinbefore described the upper part of the sock or stocking will closely fit the leg and be supported in place, and by incorporating strands of elastic during the knitting 30 of the hosiery on the machine the supporting means can be added without increasing the cost as in the case where hems or pockets are provided or elastic bands used, 35 the single strands being picked up by the machine at intervals and interwoven with the threads or yarn.

I claim:—

1. In combination with a stocking having a 40 ribbed upper portion, of means for supporting the stocking in place comprising lengths or strands of elastic extending around the upper end of said ribbed portion and knitted with the yarn of the fabric for 45 interlocking engagement therewith, the ends of said strands of elastic being turned abruptly backward and also knitted in the fabric.

2. In combination with a stocking having 50 a ribbed upper portion, of means for supporting the stocking in place comprising separate spaced apart lengths or strands of elastic extending around the upper end of said ribbed portion and knitted with the yarn of 55 the fabric for interlocking engagement therewith, the ends of said strands of elastic being turned backward and also knitted in the fabric.

ANDERSON C. GRASHAM.
